UNITED STATES PATENT OFFICE.

JAY ROSE, OF BROOKLYN, NEW YORK, ASSIGNOR, BY MESNE ASSIGNMENTS, TO HENRY EISENSTADT, OF BROOKLYN, NEW YORK.

DOUCHE NOZZLE.

Application filed May 14, 1919, Serial No. 297,062. Renewed March 3, 1927.

This invention relates to improvements in douche nozzles, such as are used chiefly in cleansing and irrigating, or in conveying liquid medicaments to the internal parts of 5 the vaginal cavity.

The interior structure of this cavity is such that jets, streams or sprays from ordinary nozzles act merely superficially, and, regardless of the force used, fail to reach the 10 interstices formed by the sinuous folds or convolutions of the overlapping membranes which constitute its enveloping walls.

It is essential when irrigating this cavity that the entire interior tract surfaces be subjected to treatment, preferably in an easy, 15 safe and convenient manner, without discomfort or pain, a condition which, so far as is known, has never been satisfactorily met.

20 Due to the peculiar construction and disposition of these flexible and pliable membranous walls they are readily dilated or distended and instruments for such purposes are in use by surgeons, but so far as I am 25 aware, no device is commercially known that may be freely used in safety by the individual herself.

The principal object of this invention is to provide a douche nozzle which fulfills 30 the foregoing conditions, effectually and painlessly expanding the vaginal cavity, loosening the folds of the membranes to such an extent that liquid supplied by the device is brought into intimate contact with the 35 surface, thoroughly flushing the same.

A further object is to provide a douche 40 which can be safely used even by inexperienced persons, the operations of insertion and expansion being of the most simple and elementary nature.

A further object of the invention is to 45 provide a nozzle which will allow an easy and continuous outflow of the water or other liquid discharged through the nozzle so that the force of the discharge and the consequent cleansing effect will not be impaired.

Still another object is to provide such 50 nozzles in forms which may be thoroughly cleansed and rendered antiseptic, and which, due to the simplicity of construction, can be manufactured at a moderate cost.

55 Figure 1 is a longitudinal sectional view taken substantially through the center of a douche provided with a nozzle, made in ac-

cordance with the invention, the dilators being shown in a folded position; and

Fig. 2 is a fragmentary side elevational view of the same, the dilators being shown extended.

Referring to the drawings, 1 indicates a base piece or nipple to which the rubber tube from the ordinary douche bag may be attached. This piece has a central bore for the passage of the water or other liquid and at 60 its outer end this bore is somewhat enlarged and threaded to receive the correspondingly threaded end of an inner tube 2 whose bore forms a continuation of the water passage through the piece 1. The tube 2 is provided with an enlargement 3 at its outer end, here shown as integral with the tube, the enlargement being formed with a series of pockets 4 for receiving dilators 5 when in the closed position indicated in Fig. 1. As shown, the 65 dilators are four in number and are symmetrically arranged around the circumference of the tube, but a greater or less number may obviously be employed if desired.

The dilators and pockets terminate somewhat short of the end of the enlargement 3, which is formed of a perforated cap 6 through which the water or other liquid is discharged, the tube walls between the 70 pockets 4 being also preferably perforated to distribute the liquid over the entire surface of the walls of the cavity to be irrigated or treated. The end cap 6 is made detachable to permit the ready insertion of 75 a sponge or gauze containing a medicated 80 solution to be sprayed on the surface by the water from the tube 2.

The dilators 5 are pivoted on a sliding collar or sleeve 7 supported on the tube 2 immediately below the expanded portion 3 85 and the shoulder between the tube 2 and the expanded portion is shaped so as to act as a cam to force the dilators out on their pivots into their expanded position shown in Fig. 2 as the sleeve 7 is moved forward on the tube 90 2 in Fig. 1, that is, a bow-shape, their outer ends being turned inward to lie well within the pockets 4 when the dilators are contracted while the middle convex portions of the 95 dilators are substantially flush with the circumferential wall of the enlargement so as to present no projecting parts to engage and irritate the delicate surface of the cavity.

The mechanism for shifting the sleeve 7 along the tube 2 to operate the dilators may 100 105 110

be of any suitable design, but I prefer to employ for the purpose a pair of arms or links 8 pivoted to the lower edge of the sleeve 7 at diametrically opposite points, the links 5 being preferably extended through holes in a guide collar 9 formed on the tube 2 at the point indicated, and connected at their lower ends to the forked end of a bell crank lever 10 pivoted in a block 11 attached to the tube 10 2 near its outer end. The forked end of the bell crank embraces the tube 2 as shown, and its other end is formed to provide a thumb-piece or handle 12 by means of which the bell crank is operated, the arrangement being such that the sleeve 7 will be raised or 15 pushed outward when the thumb-piece is pressed toward the nipple 1.

In order that the dilators may be readily 20 operated with one hand, the sleeve 7 is preferably shifted in the reverse direction by springs 13 which may be arranged, as shown, on the links 8 between the collar 9 and the fork of the bell crank 10 to be compressed by the upward movement of the fork.

25 The block 11 is recessed to fit over a lug 14 on the tube 2 to which it is attached by a screw, and pivoted in a slot in the lower portion of the block is a latch 15 which projects through a slot in the bell crank 10 and 30 has its lower edge notched to engage a tooth formed at the end of the slot in the bell crank whereby the dilators may be locked in open or partially open position and thereby relieve the user from holding the thumb-piece against the pressure of the springs. The latch may be held yieldingly in engagement with the tooth by a spring pin 35 mounted in the bell crank in the manner shown.

40 The operating mechanism for the dilators is covered or enclosed by an outer sheath or casing 16 of the same external diameter as the enlargement 3 between the pockets 4, whereby when the dilators are closed the 45 instrument has a smooth tubular exterior surface from end to end.

The sheath 16 is held in place by a short sheath or casing section 17 which is notched on one side to receive the block 11 with the 50 attached bell crank 10 and latch 15. In assembling the device, after the sleeve 7 is placed on the tube 2 and the links 8 mounted in the guide 9, the sheath 16 will be slipped over the tube until its upper end abuts 55 against the shoulder 18 formed at the base of the enlargement 3. The sheath is notched as indicated at 19 at points coinciding with the pockets 4 to permit the projection of the dilators in the manner shown. The bell 60 crank 10 will then be attached to the lower ends of the links 8 and the block 11 seated on the lug 14 and fastened in place. The short sheath or casing section 17 will then be slipped over the end of the tube 2 into 65 engagement with the lower end of the sheath

16 and the sheath sections clamped in place by the attachment of the fitting 1 to the lower end of the tube 2.

The nozzle is made throughout of metal so that it may be sterilized by boiling in the 70 same way as other surgical instruments.

My improved nozzle has numerous advantages which will be obvious to the medical profession. The dilators are arranged to lie substantially within their cavities and the 75 connections between the external operating member and the dilators are entirely within the outer periphery of the nozzle so that at the entrance there is nothing to irritate or cause reflex contraction of the sphincter 80 muscle, which is not only injurious but interferes with the outflow of the liquid. Also, the shape of the dilators is such as to present a smooth and rounded surface of more or less extended area for contact with the 85 walls of the cavity to avoid all danger of injury.

It is also to be understood that while the nozzles are designed particularly for vaginal douches, they may obviously be used 90 for other purposes, and the invention is not limited to such special use.

This is a continuation in part of my co-pending application Serial No. 223,493, now Patent No. 1,434,964, dated November 7, 95 1922.

I claim:

1. A douche nozzle comprising a tube, a plurality of dilators movably supported on said tube in position to lie wholly within 100 the cavity to be irrigated and terminating short of the end of the tube, an actuating member for said dilators carried by said tube in position to lie wholly without said cavity, connections between said dilators and said actuating member comprising means for shifting the dilators longitudinally of the instrument, and cam projections on said tube for engaging and opening the dilators upon said longitudinal movement. 105

2. A douche nozzle comprising a tube, a plurality of dilators movably supported on said tube in position to lie wholly within 110 the cavity to be irrigated, an actuating member for said dilators carried by said tube in position to lie without said cavity, connections between said dilators and said actuating member comprising means for shifting the dilators longitudinally of the instrument, cam projections on said nozzle for engaging and opening said dilators upon 115 said longitudinal movement, and a sheath of no greater diameter than the maximum diameter of said tube or of said contracted dilators, said sheath completely enclosing 120 said operating connections.

3. A douche nozzle comprising a tubular member, a plurality of dilators movably supported on said tube in position to lie 125 wholly within the cavity to be irrigated, 130

and terminating short of the end of said tube, spring means for holding the dilators normally contracted, actuating means for said dilators carried by the tube in position to lie without the cavity and lying entirely at the outer end of said dilators, said means comprising a thumb-piece adapted to be pressed toward said tubular member to expand said dilators, and a latch for holding said dilators expanded, the end of the latch lying in position to be engaged by the thumb on the thumb-piece.

4. In a douche nozzle a tube having an enlarged perforated end, longitudinal grooves or pockets in said tube, dilators adapted to lie within said pockets, said dilators projecting inwardly beyond the enlargement of said tube, a sleeve supported on the smaller portion of the tube, said dilators being pivoted on said sleeve and shaped to engage the shoulder between the small and large parts of the tube when the sleeve is slid on the small part of the tube toward the enlargement thereby expanding the dilators, an operating member for said dilators at the other end of the tube, a connection between said sleeve and said operating member, and an external sheath surrounding said connections and the ends of the dilators, the outer periphery of said sheath forming a substantial continuation of the periphery of the enlarged part of the tube.

5. A douche nozzle comprising a structure of substantially uniform cross-section from end to end when adjusted for insertion into the cavity to be irrigated, said structure comprising an outer hollow sheath of tubular shape, an inner bulbous tip having discharge perforations; a constricted tubular stem having perforations and in fluid connection with said bulbous tip; a plurality of expanding dilators when contracted occupying the space about said stem and adapted to lie wholly within the cavity to be irrigated and wholly to the rear of said bulbous tip; actuating means for said dilators mounted upon the structure of said nozzle and adapted to lie wholly without the cavity to be irrigated; mutually cooperating cam formations upon said structure and upon the rear ends of said dilators for effecting the expansion and contraction of said dilators solely from their outer ends, and means providing the fluid connection through said sheath to said stem and an operating mechanical connection between said actuator and the rear ends of said dilators, said means lying wholly within said sheath.

6. A douche nozzle consisting of a structure, the cross-section of which is substantially uniform from end to end, said structure comprising a hollow bulbous front end, having fluid discharge perforations; an outer sheath adapted to fit the organ to be irrigated for protective purposes; a contracted

portion providing a fluid duct and located between the inner end of said sheath and said bulbous end and providing free space within the confines of the maximum diameter of said structure; a plurality of dilators free from all exposed connections and adapted when contracted to lie within said space and form substantially uniform continuation of the surface of said structure; an actuator for said dilators mounted on said structure and adapted to lie wholly without the cavity to be irrigated; cooperating cam means mutually formed on the outer ends of said dilators and said structure whereby relative longitudinal movement will effect the expansion of said dilators and means providing a fluid connection from the exterior end of said sheath to said stem and an operating mechanical connection between said actuator and said cam means.

7. A douche nozzle comprising a tubular sheath; expanding dilators at the distal end; a bulbous enlargement at the distal end; a nipple at the proximal end; means forming a duct and a mounting for said dilators extending from said nipple to said bulbous end; additional means for operating said dilators lying wholly within said sheath; and a bell-crank lever near the proximal end of the structure for effecting the operation of said dilators.

8. A douche nozzle comprising a tubular element having a perforated end, and a plurality of dilators carried by said tube, said dilators being pivotally mounted and thereby divided into longer and shorter arms, resilient means for normally maintaining said shorter arms in expanded position, actuating means for contracting the said shorter arms, and a control member adjacent the rear end of said tube, operatively connected to said actuating means.

9. A syringe comprising a tube having a number of perforations at one end, a casing surrounding the opposite end of said tube, a number of dilator arms movably mounted in the forward portion of said casing, control means for said dilator arms, external to the casing, and means for operatively connecting said arms and said control means.

10. A douche nozzle comprising a tube having a perforate end, a perforate bulbous tip at the perforate end of said tube, a number of dilators mounted around the perforate end of said tube, a casing surrounding the other end of said tube, and enclosing the rear ends of said dilators, slidable means contained within said casing for actuating said dilators, control means for said slidable means carried partly within said casing, and extending externally through an aperture in the casing, and means within said casing operatively connecting said slidable means and said control means.

11. A douche nozzle comprising a tube

having a number of dilators pivotally mounted thereon, a casing around the rear end of said tube enclosing the rear ends of said dilators, resilient means contained within said casing for normally maintaining the dilators in contracted position, operating means for said dilators comprising a sliding member mounted on said tube and contained within said casing, and means partly external to said casing for actuating said sliding member.

12. A douche nozzle comprising a tube having at one end a bulbous tip, said tube and said bulbous tip having a number of discharge perforations, a number of dilators pivotally mounted around the inner end of said tube, a casing around the outer end of said tube enclosing the shorter ends of said pivoted dilators, a slidable member within said casing for actuating said dilators, and means comprising an external member operatively connected to said slidable member for controlling the movement of said slidable member.

13. A douche nozzle comprising a tubular element having a number of perforations adjacent its inner end, a bulbous perforated tip detachably mounted at the said end, a dilator carrier mounted upon said tube, a number of dilators secured thereto and extending toward but terminating short of the inner end of said tube, a sheath around the outer end of said tubular element, and extending around the rear ends of said dilators, means for normally maintaining the dilators in an unextended position, actuating means for expanding said dilators, and control means operatively connected to said actuating means.

14. A douche nozzle having a hollow tubular sheath, a tube extending through said sheath, and having a portion extending therebeyond, said portion having at its end a bulbous tip, a dilator carrier mounted upon said tube, and a number of dilator arms pivotally secured thereto, and thereby divided into longer and shorter arms, said longer arms, when contracted, occupying the

space about the said extended portion of the tube, resilient means for normally maintaining the longer arms of said dilators adjacent to said tubular member, actuating means for expanding said longer arm and control means positioned upon the exterior of said device, operatively connected to said actuating means.

15. A douche nozzle comprising a tube, a plurality of dilators movably supported on said tube in position to lie wholly within the cavity to be irrigated and terminating short of the end of the tube, an actuating member for said dilators carried by said tube in position to lie wholly without said cavity, connections between said dilators and said actuating member comprising means for shifting the dilators longitudinally of the instrument, and cam projections associated with said tube for engaging and opening the dilators upon said longitudinal movement.

16. A douche nozzle comprising a tube having a number of perforations at one end, a casing surrounding the opposite end of said tube, a number of dilator arms movably mounted in the forward portion of said casing and extending toward but terminating short of the forward end of the tube, control means for said dilator arms external to the casing, and means for operatively connecting said arms and said control means.

17. A douche nozzle comprising a tube having a number of dilators pivotally mounted thereon, but terminating short of the forward end of the tube, a casing around the rear end of said tube enclosing the rear ends of said dilators, resilient means contained within said casing for normally maintaining the dilators in contracted position, operating means for said dilators comprising a sliding member mounted on said tube and contained within said casing, and means partly external to said casing for actuating said sliding member.

In testimony whereof I affix my signature.

JAY ROSE.
